CLOSED HEAD SOCKET-HEAD SCREW OR
BOLT

Wesley D. Webb, Milwaukee, Wis., assignor to
Mac-it-Parts Company, Lancaster, Pa., a cor-
poration of Pennsylvania

Application September 14, 1937, Serial No. 163,819

1 Claim. (Cl. 85—45)

This invention relates primarily to screws, bolts and the like which are formed with round heads or bodies provided with an axial socket either hexagonal, square, triangular or of any other 5 poly-sided shape in cross-section and by which it may be rotated by a special wrench to tighten or loosen it in a tapped hole.

The invention relates more particularly to means incorporated therein for closing the outer 10 end of the socket opening to prevent its becoming filled with dirt or other foreign matter which would require cleaning out the socket before the end of the wrench could be inserted.

The object of the invention is to provide a 15 round-head socket screw or bolt having a normally closed socket.

Another object of the invention is to provide a machine screw, bolt or the like having an axial socket in the head which is provided with a cover 20 or closure to protect and close the socket from collecting dirt, grit or other foreign matter.

Another object of the invention is to provide an article of this kind in which the socket is normally closed, but which may be readily opened to 25 receive a tool or wrench by which it may be rotated.

A further object of the invention is to provide a closing means for a socket which may be depressed into the socket by the insertion of a tool 30 or wrench preparatory to rotating the article.

With these and other objects in view, my invention consists in certain novel construction and combination of parts as will hereinafter be fully described and claimed and further illustrated in 35 the accompanying drawing which forms a part hereof and in which like figures of references refer to corresponding parts in all of the views, but it is understood that slight changes may be made without departing from the spirit of the 40 invention.

In the drawing:

Figure 1 shows the end of the head of a socket-head cap-screw with my invention embodied therein.

Figure 2 is a side view of a socket-head cap-screw showing the head in section to illustrate the construction and combination of parts.

Figure 3 is a vertical sectional view of a socket-head cup point set-screw showing my invention as applied thereto.

Figure 4 shows a vertical sectional view of a socket-head cap-screw with my invention incorporated therein and showing the position assumed by the closure cap when the end of a

wrench is inserted into the socket upon the closure cap.

Figure 5 shows a top plan view of the closure cap.

Figure 6 shows a sectional view of the same. 5

Figure 7 shows a vertical sectional view of a socket-head pipe lug in which my invention is incorporated.

Referring to the drawing:

In Figures 1, 2 and 4, I have shown the usual 10 type of socket-head cap-screw, comprising a round head 10, formed on the shank 11 and provided with the external threads 12.

The head 10 is formed with the axial hexagonal socket 13 for the reception of a bar-wrench or 15 other tool by which the screw may be rotated.

Communicating with the lower or closed end of this socket 13 is formed an axial recess 14 of smaller diameter than that of the socket, and again communicating with this recess is a threaded hole 15, within which is threaded the lower end of a pin 16 which is provided with a head 18 20 the end of which is flush with the end of the head 10.

Slidably mounted on this pin 16 and forming a 25 slide fit with the wall of the socket 13 is a closure cap or plug 17 of the same shape as that of the socket and which may be either square, triangular, hexagonal or any poly-sided shape in cross-section and this closure cap 17 is formed 30 with an axial countersunk hole 25 to fit the head 18 of the pin 16.

For normally retaining the closure cap 17 in flush relation with the end of the head 10, a spiral spring 19 is mounted on the pin 16 with its lower 35 end in the recess 14 and its upper end pressing against the under surface of the closure cap 17.

It will thus be seen that normally the closure cap 17 is held by the spring 19 with its upper face flush with both the head of the screw 16 and the 40 head 10 of the cap-screw 11.

Referring to Figure 4, it is the usual practice to employ with socket-head screws, bolts and the like, a wrench in the form of a bent bar of the same shape in cross section as the socket opening 45 in the screw or bolt, and I have here shown such a bar-wrench 23, but have formed the same with an axial bore or recess 24 in the end thereof.

In applying the bar-wrench 23 to the screw head 10, the end of the wrench is pressed downward upon the closure cap 17 forcing it downward within the socket 13 against the pressure of the spring 19, the recess 24 in the end of the wrench 23 allowing the pin 16 to enter as shown in Figure 4, and in this manner the end of the wrench 23 55

can be entered the required distance in the socket to afford a sure grip of the wrench in the socket for turning the screw. The recess 14 allows the spring 19 to be compressed therein so that the closure cap 17 may be depressed to within a short distance of the bottom of the socket 13.

As shown in Figure 3, the invention is applied to a set-screw 20 having the external threads 21 and the cup-shaped end 22.

10 As shown in Figure 7 of the drawing, the invention is applied to a pipe lug 26 having the external threads 27, and it is thus seen that the invention may be applied to any socket in many different articles.

Having thus described my invention, what I claim as new and desire to secure by Letters Patent, is:

A bolt having a socket in its head, a pin fixed axially in the socket and having a head thereon, the upper surface of which is in a plane with the upper surface of the bolt head, a closure plate 5 slidable on the pin and having its periphery intimately engaged with the wall of the socket, and a spring in the socket and engaged with the plate 10 to hold the same yieldably engaged with the head of the pin and the upper surface of the plate in a plane with the upper surface of the bolt head.

WESLEY D. WEBB.
